UNITED STATES PATENT OFFICE

LAURENS HAMMOND, OF EVANSTON, ILLINOIS, ASSIGNEE, BY MESNE ASSIGNMENTS, TO THE HAMMOND CLOCK COMPANY, OF CHICAGO, ILLINOIS, A CORPORATION OF DELAWARE

ALTERNATING-CURRENT CLOCK

Application filed June 18, 1929. Serial No. 371,751.

My invention relates generally to alternating current clocks of the synchronous motor driven type and more particularly to improvements in the gear train by which the motor is connected to the hands of the clock and to the method of mounting the motor in the clock frame.

It is one of the objects of my invention to provide an improved gear train for clocks which are driven from the high speed end of the train, having the minimum number of gears and shafts compatible with compactness and ease of assembly.

A further object is to provide an improved means for mounting the motor parts upon the clock frame whereby parts of the motor form reinforcements for the frame and whereby the magnetic forces on the armature of the motor tending to twist the frame are minimized.

A further object is to provide an electric motor driven clock which is simple in construction, may be readily made in quantity production, may be easily assembled, and which may be economically manufactured.

Other objects will appear from the following description, reference being had to the accompanying drawings, in which

Fig. 1 is a front elevation of the clock mechanism, portions of the dial and gears being broken away;

Fig. 2 is a bottom plan view of the clock mechanism, the dial being shown in section;

Fig. 3 is a right side elevation of the mechanism shown in Fig. 1;

Fig. 4 is a vertical section taken on the line 4—4 of Fig. 6;

Fig. 5 is a developed view of the gear train; and

Fig. 6 is a section taken on the line 6—6 of Fig. 3.

The clock of my invention comprises two frames 10 and 12. The frames are joined and held rigidly in suitably spaced relation

to the frame 12 and the other end passing through the frame 10 and secured thereto by a nut 16.

The motor used to drive the clock comprises a plurality of substantially U-shaped laminations forming a core 18, several of the laminations of which project downwardly to form pole pieces 20. A coil 22 is wound around one of the legs of the U-shaped core 18, and the frame 12 has a suitable rectangular notch 24 cut therein to receive the coil 22. The core 18 is secured to the frame 12 by three bolts 26 which pass through the frame and core, the core being separated from the frame by suitable washers 28. The core is thus attached to the frame at three points and accurately positioned relative thereto.

A rotor 30 which comprises a magnetic disc having teeth formed on its periphery is rigidly secured to a rotor shaft 32 which is journaled in suitable bearings 34. The bearings are formed in bosses on plates 36, to which plates oil retaining cups 38 are secured.

The rotor shaft 32 has a sleeve 40 rigidly secured thereto, the latter carrying a casing 42 which may contain a viscous liquid and a loosely mounted fly-wheel or other suitable means for preventing hunting of the armature and for making the motor automatically fall into step when launched at a speed above synchronism. This mechanism is more fully disclosed and claimed in my co-pending application, Serial No. 364,480, filed May 20, 1929, Patent No. 1,719,805, granted July 2, 1929.

A pinion 44 is also rigidly secured to the shaft 32, this pinion meshing with a gear 46 which is rigid with a pinion 48 and with a shaft 50. A gear 52 which is rigidly connected to a pinion 54, and both of which are loosely mounted upon an intermediate shaft 56, meshes with the pinion 48. A gear 58 and a pinion 60 are fastened to a second hand shaft 62, the former meshing with the pinion 54 and the latter with a gear 64.

rigidly secured to the shaft 56. A pinion 66 is rigidly secured to the forward end of the shaft 56 in front of the frame 10 and this pinion meshes with a gear 68 which is rotatable on shaft 62 and is frictionally held against a pinion 72 by a spring 73. The pinion 72 is rigidly secured to the minute hand sleeve 70 and is in mesh with a gear 74. The gear 74 and a pinion 76 are rigidly secured to the forward end of a setting shaft 78 and which journalled in the frames 10 and 12. The pinion 76 meshes with a gear 80 which is rigidly secured to the hour hand sleeve 82. A second hand 84 is secured to the end of the second hand shaft 62, a minute hand 86 is secured to the sleeve 70, and an hour hand 88 is secured to the sleeve 82.

The hands 84, 86 and 88 register with a suitable dial 90 which is suitably supported either from the frame 10 or from the casing in which the clock mechanism is mounted. This dial has a suitable aperture 92 through which a segmental disc 94 may be observed, the disc being secured at the forward end of the shaft 50. During the operation of the clock this disc, which is preferably enameled a color contrasting with that of the dial of the clock, serves as a flashing indication that the clock is running. The rearward end of the shaft has a suitable thumb-piece 96 secured thereto, this thumb-piece serving as a means for starting the clock. The shaft 78 has a suitable knurled thumb-piece 98 secured at its rearward end by which the clock may be set.

It will be especially noted, from Figs. 1, 2 and 4, that the previously described gear train is of extremely simple construction and is so arranged as to be very compact and make possible the installation of this mechanism in a small clock. The fact that the gear 52 and pinion 54 are freely mounted on the shaft 56 makes possible the elimination of a shaft which was formerly considered necessary.

It will be observed that the pole pieces 20 are relatively close to the frame 12 so that the magnetic pull exerted upon the rotor does not tend to warp or cant the frames relative to each other and thus any tendency of the various shafts to bind in their bearings is prevented. Furthermore, the resultant of the magnetic forces acting upon the rotor is upwardly, thus counteracting the force of gravity acting upon the rotor and parts connected therewith and relieving the rotor bearings of a great deal of the frictional load which would otherwise be present, and thereby greatly extending the life of the clock.

To start the clock it is necessary merely to manually twirl the thumb-piece 96 a single time at sufficient speed so that the rotor 30 will be revolving at super-synchronous speed. As the rotor slows down to synchronous speed, due to the frictional load im-

posed by the gear train, it will fall in step and continue rotation at synchronous speed. The rotor thus drives the hour hand of the clock through the following gear train: pinion 44, gear 46, pinion 48, gear 52, pinion 54, gear 58, shaft 62, pinion 60, gear 64, shaft 56, pinion 66, gear 68, pinion 72, gear 74, pinion 76, and gear 80. The minute hand is of course rotatable with the gear 72 and the second hand rotated by the shaft 62. The shaft 50 will rotate at approximately one revolution per second and the rotation of the disc 94 may readily be observed through the opening 92 in the dial to show that the clock is operating.

In setting the hands of the clock the thumb-piece 98 is rotated in the proper direction and through the gear 74 and pinion 72 the pinion 76 and the gear 80 will rotate the hands. The bearings 34 and the ends of the shaft 32 are the only parts of the clock which are subject to substantial wear and since the load on these bearings is appreciably lessened, due to the fact that the resultant of the magnetic forces acts upwardly, and since the bearings are continuously supplied with lubricant from the cups 38, the clock will run for a very long period of time without any attention.

The invention is capable of wide variation within equivalent limits and I contemplate such variation as may be desirable or useful in the particular adaptation of the invention shown, or in its adaptation to other devices.

I do not restrict myself in any unessential particulars, but what I claim and desire to secure by Letters Patent is:

1. An electric motor driven clock, comprising a shaft geared to said motor and having a pinion secured thereto, a second hand shaft, an intermediate shaft, a rigidly connected gear and pinion driven by said first-named pinion and mounted for free rotation on said intermediate shaft, and a train of gearing driven from said gear and pinion and through said second hand shaft and said intermediate shaft.

2. In a motor driven clock having indicating hands and having a gear train in which the drive is from the high speed gears to the low speed gears, a motor pinion; a gear, a spur pinion and shaft rotatable as a unit and the gear thereof meshing with said motor pinion, an intermediate shaft, a gear and a pinion rotatably mounted on said intermediate shaft, the gear thereof meshing with said spur pinion, a second hand shaft, a pinion and gear rigidly mounted on said second hand shaft, said last-named gear meshing with said pinion rotatably mounted on said intermediate shaft, a gear rigidly secured to said intermediate shaft and meshing with the pinion on said second hand shaft, and means for driving the hour and minute hands from said intermediate shaft.

3. In a speed reduction gearing for motor driven clocks driving from the high speed end of the train, a pinion (48) rotated by the clock motor, an intermediate shaft, a gear and pinion fixed relative to each other but rotatably mounted on said intermediate shaft, a second shaft, a gear and a pinion rigidly mounted on said shaft, said last-named gear meshing with the said pinion which is rotatable on said intermediate shaft, a gear fixed to said intermediate shaft and meshing with the pinion on said second shaft, and means for driving the clock hands from said intermediate shaft. 70
- 10 4. In a motor driven clock having an indicating hand driving gear train in which the drive is from the high speed gears to the low speed gears, a pinion (44) on the motor shaft, a gear (46), pinion (48), and shaft (50) rotatable as a unit and the gear (46) meshing with said pinion (44), an intermediate shaft (56), a gear (52) and a pinion (54) rotatably mounted on said intermediate shaft, the gear (52) meshing with said pinion (48), a second hand shaft (62), a pinion (60), and gear (58) rigidly mounted on said second hand shaft, said gear (58) meshing with said pinion (54), a gear (64) rigidly secured to said intermediate shaft and meshing with said pinion (60), a pinion (66) rigidly secured to said intermediate shaft, and gearing meshing with said pinion (66) for driving the indicating hands. 75
- 15 5. In an electric motor driven clock having a gear train, a pair of frames, one of said frames having a notch cut therein, an inverted U-shaped core secured to said notched frame and lying between the two frames, a winding about said core, said winding lying partially within the notch in said frame, a motor armature rotatably mounted in said frame, and pole pieces formed on said core at the lower end thereof for cooperation with said armature. 80
- 20 6. In an electric motor driven clock, a frame comprising a pair of spaced rigidly joined plates, a gear train mounted on said frame, a rotor, a shaft bearing said rotor, carried by said plates and geared to said train, a laminated core secured adjacent one of said plates on its inner side, and a coil wound about a portion of said core and extending beyond the outer surface of one of said plates. 85
- 25 7. In an electric motor driven clock, a frame comprising a pair of spaced rigidly joined plates, one of said plates having a recess formed therein, a motor armature, a gear train mounted on said frame and driven by said armature, and a core for said armature rigidly secured to said recessed plate and forming a reinforcing bridge across said recess. 90
- 30 8. In an electric motor driven clock having a gear train, a pair of frame plates for

In witness whereof, I hereunto subscribe my name this 17th day of June, 1929.

LAURENS HAMMOND.
